UNITED STATES PATENT OFFICE.

THOMAS E. DROHAN, OF SCHENECTADY, NEW YORK, ASSIGNOR TO GENERAL ELECTRIC COMPANY, A CORPORATION OF NEW YORK.

CONTACT FINGER AND METHOD OF MAKING THE SAME.

1,415,320.

Specification of Letters Patent.

Patented May 9, 1922.

Application filed December 17, 1920. Serial No. 431,522.

To all whom it may concern:

Be it known that I, THOMAS E. DROHAN, a citizen of the United States, residing at Schenectady, in the county of Schenectady, 5 State of New York, have invented certain new and useful Improvements in Contact Fingers and Methods of Making the Same, of which the following is a specification.

My invention relates to a contact finger 10 for making and breaking electric circuits and has for its object the production of a simple and reliable contact finger in an efficient and economical manner.

Contact fingers when forged or cast are 15 very likely to have rough and uneven contact surfaces which will cause poor contact in operation. It has also sometimes been the practice to punch or bore holes entirely through the contact finger for the purpose of 20 attaching supporting pins. In such case, it is difficult to finish off the ends of the pins so as to be flush with the face of the contact finger. I overcome these disadvantages by shaping the contact finger in a die, thereby 25 giving it a smooth and even contact surface, and by embedding the heads of the supporting pins in the body of the finger so that the contact surface is maintained unbroken.

My invention provides for the production 30 of contact fingers in a very economical manner.

Other objects and features of my invention will appear in the course of the following specification in which I have shown my 35 invention embodied in concrete form for the purpose of illustration.

In the accompanying drawing Fig. 1 is a perspective view of a contact finger embodying my invention, while Figs. 2, 3, 4 and 5 40 show the various successive steps in the making of contact finger in accordance with my invention.

Referring to Fig. 2 of the drawing, a strip of soft copper or other conducting metal 10 45 is cut to the requisite length and holes 11 and 12 punched or bored near the ends thereof. The next step in the making of the contact finger, in which a portion of the metal strip 10 at each end is bent laterally upward 50 and over, is shown in Fig. 3. The portion bent upward at the left end is longer than the portion bent upward at the right end to provide for a curved contact or "wiping" surface 15 as will presently appear. A sufficient angle is left between the end portions 55

and the central portion to permit supporting pins 13 and 14 to be inserted in an upward direction through holes 11 and 12 into positions as shown in Fig. 4. The piece is now placed in a die where it is shaped to final 60 form, the end portions being folded downward upon the central portions, as shown in Fig. 5, and the portion to the left of pin 14 being bent slightly upward to form a curved contact or "wiping" surface 15. The heads 65 16 and 17 of the supporting pins are wedged tightly in the holes and between the end portions and the central portion, thereby holding the pins firmly in place. As shown in the drawing the ends of the strip will abut 70 against each other.

The contact surfaces 15 and 18 will be smooth and even by reason of their engagement under great pressure with the surface of the die. By using this method of attaching the supporting pins it is not necessary to make holes in the surface 18 which therefore remains unbroken.

In the first operation the strip of metal of desired length may be cut, the holes 80 formed, and the end portions bent upward, as shown in Fig. 3. The supporting pins are next inserted, and then the hole is placed in a die and shaped to final form in one operation as shown in Fig. 5. 85

While I have here shown an embodiment of my invention which is, at present, the best means known to me, I would have it understood that I do not limit my invention thereto, since various modifications thereof 90 will suggest themselves to those skilled in the art without departing from the spirit of my invention, the scope of which is set forth in the annexed claims.

What I claim as new and desire to secure 95 by Letters Patent of the United States, is:

1. A contact member formed of a strip of metal having a pin passing through a portion thereof, the portions of the strip being folded onto each other. 100

2. A contact member formed of a strip of metal having a headed pin passing through a portion thereof, the portions of the strip being folded onto each other so as to inclose the head of the pin and hold the pin securely 105 in place.

3. A contact member formed of a strip of metal having a headed pin passing through an end portion thereof, said end portion being folded over onto the strip so as to inclose 110

the head of the pin and hold the pin securely in place.

4. A contact member formed of a strip of metal having each end provided with a headed pin passing through the strip and folded over onto the central portion so as to inclose the heads of the pins and hold the pins securely in place.

5. The process of making a contact member out of a strip of metal which consists in passing a pin through a portion thereof and folding the portions of the strip onto each other.

6. The process of making a contact member out of a strip of metal which consists in passing a headed pin through a portion thereof and folding the portions of the strip

onto each other so as to inclose the head of the pin and hold the pin securely in place.

7. The process of making a contact member out of a strip of metal which consists in passing a headed pin through an end portion thereof and folding said end portion over onto the strip so as to include the head of the pin and hold the pin securely in place.

8. The process of making a contact member out of a strip of metal which consists in passing a headed pin through each end of the strip and folding the ends over onto the central portion so as to inclose the heads of the pins and hold the pins securely in place.

In witness, I have hereunto set my hand
this 15th day of December, 1920.

THOMAS E. DROHAN.
